UNITED STATES PATENT OFFICE.

JEAN CASTRO, OF BROOKLYN, NEW YORK, ASSIGNOR TO FRANK & COHEN SILK CORPORATION, A CORPORATION OF NEW YORK.

DESIGN FOR A TEXTILE FABRIC OR SIMILAR ARTICLE.

Application filed October 22, 1928. Serial No. 28,584. Term of patent 3½ years.

To all whom it may concern:

Be it known that I, JEAN CASTRO, a citizen of the United States, residing at Brooklyn, in the county of Kings and State of New York, have invented a new, original, and ornamental Design for a Textile Fabric or Similar Article, of which the following is a specification, reference being had to the accompanying drawing and to the accompanying sample of goods bearing the design, forming a part thereof.

The figure on the drawing is a plan view of a piece of textile fabric bearing my new design which is intended to be carried forward or repeated ad libitum, a single unit of my design being comprised within the area defined by the indicating arrows shown on the drawing. The shading is on the drawing only to indicate more or less contrasting colors and not to indicate specific colors.

I claim as my invention:

The ornamental design for a textile fabric or similar article substantially as shown and described.

JEAN CASTRO.
